Application September 16, 1952, Serial No. 21,487

Term of patent 14 years

(Cl. D72—1)

To all whom it may concern:

Be it known that I, James R. Ferguson, a citizen of the United States, residing at Bristol, State of Tennessee, have invented a new, original, and ornamental Design for a Traffic Signal, of which the following is a specification, reference being had to the accompanying drawing, forming a part hereof.

Figure 1 is a front elevational view of a traffic signal showing my new design;

Figure 2 is a top plan view thereof;

Figure 3 is a rear elevational view; and

Figure 4 is a bottom plan view.

The characteristic features of my design re-

side in the front face as shown in Figure 1.

I claim:

The ornamental design for a traffic signal, as shown and described.

JAMES R. FERGUSON.
